UNITED STATES PATENT OFFICE

152,046

DESIGN FOR A BEACH SANDAL BASE

Alan B. Vickers, San Jose, Calif.

Application July 1, 1947, Serial No. 140,048

Term of patent 3½ years

(Cl. D7—5)

To all whom it may concern:

Be it known that I, Alan B. Vickers, a citizen of the United States, residing in the city of San Jose, county of Santa Clara, and State of California, have invented a new, original, and ornamental Design for a Beach Sandal Base, of which the following is a specification, reference being had to the accompanying drawing, forming a part thereof.

Fig. 1 is a rear view of a beach sandal base, showing my new design;

Fig. 2 is a bottom view of the same; and

Fig. 3 is a side view of the same.

I claim:

The ornamental design for a beach sandal base, substantially as shown.

ALAN B. VICKERS.
